(57) **CLAIM**

The ornamental design for an electronic device, as shown and described.

DESCRIPTION

FIG. 1 is a perspective view of an electronic device showing our new design;

FIG. 2 is a rear perspective view thereof;

FIG. 3 is another rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view of a second embodiment thereof;

FIG. 11 is a rear perspective view thereof;

(Continued)

FIG. 12 is another rear perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof; and,

FIG. 18 is a bottom view thereof.

The broken lines illustrate structure or features which form no part of the claimed design.

The relatively light shade lines on the surface portions indicate contour and not surface decoration.

The claimed design extends up to and includes the edges of the input port openings, circular features, and vent features on the rear surface of the device. No interior features of the ports, circular features, or vent features form part of the claimed design.
